(57) **CLAIM**

We claim a security bolt, as shown and described.

DESCRIPTION

FIG. 1 is a perspective view of the security bolt according to one embodiment of the new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines represent portions of the security bolt and form no part of the claimed design.
